(57) **CLAIM**

(51) **LOC (8) Cl.** 24-01

The ornamental design for an x-ray apparatus for medical treatment, as shown and described.

(52) **U.S. Cl.** **D24/158**

DESCRIPTION

(58) **Field of Classification Search** D24/158-161,

FIG. 1 is a front, top and left side perspective view of an x-ray apparatus for medical treatment, showing my new design;

D24/183; 378/178-190, 193, 195-198, 208,

FIG. 2 is a rear, top and right side perspective view thereof;

378/209, 10, 11, 37-39

FIG. 3 is a front elevational view thereof;

See application file for complete search history.

FIG. 4 is a rear elevational view thereof;

(56) **References Cited**

FIG. 5 is a top plan view thereof;

U.S. PATENT DOCUMENTS

FIG. 6 is a bottom plan view thereof;
